UNITED STATES PATENT OFFICE.

ALBERT A. WENTWORTH, OF MERCED, CALIFORNIA.

NECKTIE-FASTENER.

SPECIFICATION forming part of Letters Patent No. 416,386, dated December 3, 1889.

Application filed March 6, 1889. Serial No. 302,147. (No model.)

To all whom it may concern:

Be it known that I, ALBERT A. WENTWORTH, a citizen of the United States, residing at Merced, in the county of Merced and

5 State of California, have invented certain new and useful Improvements in Necktie-Fasteners, of which the following is a specification.

In the accompanying drawings, Figure 1 is 10 a view in perspective of my necktie, with shield or plate in position and slotted, and stud-holding plate removed. Fig. 2 is a back view, also in perspective, of the slotted and stud-holding plate. Fig. 3 is a front view of 15 the same in perspective. Fig. 4 is a front view in perspective of Figs. 2 and 3, and Fig. 5 is a view in perspective of shield-plate, with spring-arms removed.

My invention relates especially to fasteners employed for securing a necktie or scarf to the person of the wearer, and has for its object the production of a device which is moderate in cost and more easy of adjustment and certain in action than devices heretofore 25 employed for the purpose.

The invention will first be described in connection with the drawings, and then pointed out in the claims.

Referring to the drawings, A and B are 30 the locking and holding plates which comprise my invention. The former, or that plate represented by the letter A, is formed with two spring arms or bands *a a*, conforming to the shape of the neck, while the lower 35 part forms a shield. This plate is also pierced with a stud or pin hole *b* and two transverse slots or openings *c d* to receive the holding-tongues of the plate B, to be herein-after described.

40 The openings *b c d*, as well as that represented at C^X, may be stamped from thin sheets of metal, comprising the plate and shield, and the whole covered, save and except the two slots and stud or pin hole, with 45 cheaper material than that which forms the front or scarf portion.

The locking-plate B is stamped out and bent or curved as shown, and to the bent upper member is permanently fixed a stud 50 or pin *f*, having a head or button *g* formed upon one end only. Beneath the pin is

formed an outwardly-projecting tongue *h*, while the lower end of the plate is slotted at *i*, and has an upwardly-extending lip *j* and a downwardly-extending pin *K*.

55

In practice the band of the shirt D is buttoned to the head or button of the stud or pin *f* upon the reverse side of the upper bent member of the locking-plate B, with the pin projecting outward, as shown in Fig. 4, and the 60 plate lying along the center plait of the shirt, in which position the button-holes of the collar of the wearer receive the projecting pin or stud *f*, and thereupon the scarf, with its plate and band, is adjusted to the neck, the 65 projecting pin of the locking-plate entering the hole or perforation *b* and the tongue *h* the transverse slot *c*, in which position the scarf is slightly raised or pushed upwardly and the locking-plate drawn downwardly, so 70 that the lip *j* will catch on the upper slot *d* of the plate or shield A, whereby the tie is held firmly in place.

In order to remove the tie quickly, the finger is applied to the lower end of the shield 75 and the tie slightly raised, which releases the lip *j* from its catch and permits the wearer to instantly remove the tie from the neck.

Having thus described my invention, what I claim, and desire to secure by Letters Patent, 80 is—

1. The necktie-fastener herein described, which consists in a shield carrying a spring or flexible neck-band and provided with a hole or perforation and an upper and lower 85 transverse slot, in combination with a detachable locking-plate carrying a shirt band and collar holding pin or stud, as described.

2. In a necktie-fastener, the combination, 90 with a shield carrying a flexible neck-band pierced for a stud or a pin and provided with an upper and lower slot, of the detachable locking-plate having a stud or pin upon the upper bent member thereof, and a tongue and lip to engage with the slots of the shield, as 95 in the manner described.

In testimony that I claim the foregoing I have hereunto set my hand and seal.

ALBERT A. WENTWORTH. [I. S.]
